UNITED STATES PATENT OFFICE.

MAX BAILLY, OF BRUSSELS, BELGIUM.

SPARKING PLUG FOR EXPLOSION AND OTHER ENGINES.

Application filed July 28, 1922, Serial No. 578,233, and in Belgium July 30, 1921.

This invention relates to improvements in spark plugs for internal combustion engines, the object of the invention being to effect improvements in the construction of the plug 5 whereby it is prevented from becoming fouled by carbon deposits and its efficiency is increased.

With the above and other objects in view the invention consists in the construction, 10 combination and arrangement of devices hereinafter described and claimed.

Several constructions according to the invention are illustrated by way of example in the accompanying drawings in which:

15 Fig. 1 is a central longitudinal section of a plug with multiple electrodes.

Fig. 2 is a cross-section on the line A—B of Fig. 1.

20 Fig. 3 is a central longitudinal section of a modified construction of the plug.

Fig. 4 is a cross-section, on the line C—D of Fig. 1.

25 Figs. 5 and 6 are sections similar to those of Figs. 1 and 2 of another modified construction.

Fig. 7 shows a ring for regulating the length of the ignition spark.

With reference to the drawings, and especially to Figs. 1 and 2, the central conductor rod 1 to which is connected in the usual manner the current supply wire, terminates at an intermediate point of the length of the plug in a flange or disc 2. This rod is mounted in the interior of the porcelain 4 or 30 other insulating material, into which fits with a tight lateral joint a part 5, also of porcelain or other suitable insulating material. A recess in the base of the said part 5 constitutes a disruption chamber or chamber for the passage of sparks between the said disc 2 and a series of electrodes 3, embedded in the insulating material 5. These electrodes terminate close to the usual sparking points of the plug and produce at these ends the usual ignition spark which appears between the electrodes and the body of the plug F.

It will be understood from the foregoing 50 that, owing to the tight joint between the two insulating cores of the plug, the spark which appears between the end disc of the rod 1 and one of the conducting rods 3, is unable to reach the inner end of the plug and therefore ground. The spark passes through the chamber 8 of the end disc 2, first to one rod 3, then to another owing to

the movement of the ball 19. The spark appears therefore between the disc or flange terminating the central rod proper, and one or another of the conductors which lead to 60 the sparking points. This conductor, on the appearance of the spark, supplies the ignition spark between its other end and one of the sparking points 9 of the plug. The spark therefor is reinforced by the disruption of the current on the central path of the current, and on that account any deposit is destroyed by fusion. Moreover, even should one of the electrodes become fouled, there is still left a free passage for the current through the other electrodes and conductors.

With reference to Figs. 3 and 4, the tight closing of the chamber 8 for disruption of spark or sparks, is obtained owing to the 75 taper of the insulating material 5 in which are embedded the electrodes. The tightening is effected by means of the nut F² which acts on the upper insulating material or porcelain 4 and is screwed into the nut F¹ 80 which receives the lower conical insulating material. 19 is a ball of steel or other suitable material which rolls freely between the upper ends of the electrodes 3 and the upper surface of the lower insulating material 5, 85 thus forming an automatic disrupter-distributor. As this ball does not touch the conducting disc 2 which is a diametrically enlarged part of the electrode 1, a disruption spark is produced between the electrode 1 90 and the ball 19, and the current passes thence to one of the electrodes 3 by direct contact or by a new disruption spark. By this construction and the provision of the ball 19 which is movable in all directions the movement of disruptions or breaks of the current on its passage into the plug is increased and an ignition spark is produced which is of a particularly high temperature such as is required for the fusion of any carbon deposit 95 which may tend to form. Between the live electrode and the inner end of shell F of the plug appears the ignition spark for the engine.

With reference to Figs. 5 and 6 which 105 show a plug of a large size, the inner end or shell F is cylindrical both outside and inside, and receives the upper and lower insulating material held by the nut F². Between the said material is provided the 110 spark chamber 8. The lower insulator is built up of two parts 5, 5¹ which engage

with each other, the electrodes 3 being, after mounting and tightening flush the upper surface of the said insulator. Owing to this engagement a better joint is obtained in 5 mounting the electrodes in the insulating material.

The electrodes 3 are enlarged at their lower ends as at 11 to form flanges to hold washers 10 which play freely on the said end 10 so as to be able to move along the electrodes 3, and parallel to the plug walls F which act as ground electrodes in order to produce a supplementary disruption. These disruption 15 sparks appear therefore between the disc 2 and the ball 29, between the ball 29 and the upper end of an electrode, between a washer on the lower end of the electrode, a washer of the adjoining (neutral) electrode and the inner end or shell of the sparking 20 plug.

With reference to Fig. 7 the inner end of the plug has at its inner terminal part a fixed washer 10, the inner section of which follows three axes of a circle, eccentric relatively to the center of the washer. According 25 to the position of the electrodes 3 relative to the said washer, the length of the ignition spark is more or less great, since the distance between the ends of the electrodes 30 and the nearest point of the washer will vary.

It must be understood from the foregoing that the plug with multiple disruptors and automatic distributor, such as is described 35 in the foregoing, never becomes sooted up for the following three reasons: the high temperature of the ignition spark; the relative mobility of the parts between which the choking or sooting up might take place, and 40 the failure of the distributor to be affected by the influence of the electrodes in short-circuit.

The constructions hereinbefore described

may obviously be applied in the case of 45 plugs in which the usual single conductor is replaced by any desired number of conductors (two, three, four, etc.).

Claims:

1. A sparking plug for internal combustion engines comprising an insulating core 50 having a plurality of members and a chamber provided between two of said members, a plug body in which said core is arranged, said body having sparking points at its inner end, a central conducting rod extending 55 to one side of said chamber, a plurality of electrodes in the other side of said chamber extending to and projecting from the inner end of the core and an automatic distributor-disruptor comprising a conductor 60 member arranged and movable in all directions in said chamber, and active by its movement to produce current disruption sparks between itself, the end of said central-conducting rod and the adjacent end of one 65 or the other of the said plurality of electrodes and thereby produce a spark between the last named electrode and one of the sparking points.

2. A sparking plug for internal combustion engines comprising an insulating core 70 having a plurality of members and a chamber provided between two of said members, a plug body in which said core is arranged, a central conducting rod extending to one side 75 of said chamber, a plurality of electrodes in the other side of said chamber extending to and projecting from the inner end of the core and conducting members on the end of the electrodes and active to produce a further disruption spark between themselves 80 and the inner end of the body of the plug.

In testimony that I claim the foregoing as my invention, I have signed my name.

MAX BAILLY.
